UNITED STATES PATENT OFFICE.

WILLIAM LANDES, OF WICHITA, KANSAS.

PROCESS FOR PRODUCING A NEW MOTOR-SPIRIT.

1,199,909.

Specification of Letters Patent.

Patented Oct. 3, 1916.

Application filed February 9, 1915. Serial No. 7,062.

To all whom it may concern:

Be it known that I, WILLIAM LANDES, a citizen of the United States, residing at Wichita, in the county of Sedgwick and State of Kansas, have invented certain new and useful Improvements in Processes for Producing a New Motor-Spirit; and I do hereby declare the following to be a full, clear, and exact description of the invention, 10 such as will enable others skilled in the art to which it appertains to make and use the same.

This invention relates to a novel process for producing a new motor spirit by distilling crude petroleum in a manner to produce a highly inflammable and combustible oil, primarily for use in connection with any type of internal combustion motor.

One of the objects of this invention is to 20 produce a high grade of oil or new motor spirit that is richer in hydrocarbons of a volatile nature than that product of petroleum known as gasolene, which is now almost universally used for internal combustion motors.

Another object of this invention is to produce from crude petroleum a highly combustible homogeneous oil of low specific gravity containing the more highly volatile 30 and combustible components of the crude petroleum. And another object of this invention is to produce a highly inflammable and combustible homogeneous oil from crude petroleum containing the more highly volatile and combustible components of petroleum, and free from the heavier and less volatile components of the petroleum, thereby eliminating the possibility of the separation 35 of the constituents of the resulting oil by the settling of the heavier components from the lighter, and the danger of the carbonization of the working parts of the motor as is the case with the oils now in use.

These and other objects will become more 45 apparent as the nature of the invention is more clearly understood from the following specification, the subject-matter of the claim, and the apparatus illustrated in the accompanying drawings.

It is well known to the inventor of this 50 process that hitherto, it has been the practice to distil a quantity of petroleum, by leading the petroleum into a boiler which has been previously heated to a high degree of temperature. This practice has proven to be not only exceedingly wasteful, but also

to produce a very inferior grade of oil, in that, the lighter and more highly volatile components of the petroleum are rapidly and prematurely vaporized and therefore escape before the heavier and less volatile constituents are vaporized, and by this former practice, it is impossible to produce a resulting homogeneous oil of low specific gravity. The present process not only eliminates this wasteful and uneconomical feature of the old practice, but produces a homogeneous oil which contains the more highly volatile components of the crude petroleum, thus producing a light and highly inflammable and combustible oil for use in connection with internal combustion motors, which is not only more efficient in performing its functions, but owing to its highly combustible nature, is a cheaper oil by requiring a much less quantity to produce a given amount of work.

The process, constituting this invention, consists in placing the crude petroleum in a tank, or a plurality of tanks to meet the exigencies of the case, and subjecting the crude petroleum in the tank or tanks to a relatively high pressure, to force the petroleum through a conducting pipe or pipes, and through an exceedingly fine atomizer or spray nozzle projected into a steam casing which is positioned within and at one end of an elongated heated chamber which has been previously heated to a temperature of approximately 180° Fahrenheit.

The crude petroleum under pressure while within the nozzle is first heated and expanded by the steam within the steam casing which surrounds the nozzle, and is additionally treated with the steam, directed transversely of its path, as the petroleum issues from the nozzle through the restricted orifice therein and previously to its entering the heated chamber, for again expanding and dissipating the particles of the crude petroleum to insure an exceedingly fine spray of the petroleum as the same emits from the atomizer into the heated air within the heated chamber wheréin the petroleum is further expanded. By this process the crude petroleum is injected into the heated chamber in an exceedingly fine spray, whereby the lighter and more highly volatile components of the crude petroleum, such as cymogene, rhigolene, petroleum ether, and the more volatile constituents of the gasolene, are instantaneously liberated and va-

porized or gasified. Afterward the vaporized components of the petroleum are allowed to travel slowly through the heated air within the heated chamber toward the 5 opposite end of the chamber for causing the efficient separation of the vapor from the heavier and less volatile components of the petroleum, and thereafter the vapor or gas is conducted into a condenser through which 10 the vapor or gas slowly passes, resulting in a highly volatile and combustible oil of low specific gravity.

The foregoing objects, and the above described process, are readily attainable by 15 the employment of the apparatus illustrated in the accompanying drawings, in which,

Figure 1 is a side view, partly in section, showing the apparatus and its accessories. Fig. 2 is a vertical longitudinal sectional view, on an exaggerated scale, showing the detail construction of the atomizer employed. Fig. 3 is a vertical longitudinal sectional view, on an exaggerated scale, showing the detail construction of the primary 25 condensing device.

Referring to the drawings, 1 denotes the furnace structure, which may be constructed of any suitable material, 2 the fire box or combustion chamber within the furnace structure, and 3 the fuel burner, preferably employed, the burner 3 being connected to a suitable source of fuel supply, through the medium of the pipe 4, provided with the controlling valve 5.

35 Mounted within the upper portion of the furnace 1, and over the fuel chamber 2, is the elongated retort or heated chamber 6, supported upon the upper portions of the side walls of the furnace by the brackets 7. The retort or heated chamber 6 is inclined 40 downwardly toward the forward end of the furnace as shown, and has its side walls and rear end wall inclosed by the spaced shell or casing 8, for confining the heat 45 from the burner 3 around the retort or heated chamber 6, and for preventing injury to the bottom of the heated chamber 6 immediately over the burner 3, and to more evenly distribute the heat around the chamber 50 6, the chamber 6 is provided with the protector plate 9, suspended upon the chamber 6 by the straps or bands 10, which extend around the upper surfaces of the chamber 6. In the lower forward end of the chamber 55 6 is provided the manhole 11, through which foreign matter and sediment which might accumulate in the chamber 6 is removed, thus cleaning the same, and thereby preventing the clogging of the mouth of the discharge pipe 12, secured in the forward bottom portion of the chamber 6, for carrying off the heavier components of the crude petroleum during the process, and discharging the same from the end of the pipe 12, provided with the controlling valve 13, and into

any suitable receptacle, or the residuum in the chamber 6, may be conveyed to any suitable point of discharge through the branch pipe 13' connected to the discharge pipe 12.

For supplying the crude petroleum to the 70 retort or heated chamber 6, a tank or a plurality of tanks 14 are employed. The tanks 14 contain the crude petroleum, which is subjected to a relatively high pressure of approximately seventy-five pounds, supplied by any suitable means, the tanks 14 being connected to the cross pipe 15, provided with the controlling valves 16, the cross pipe 15 being connected to the common lead pipe 17, provided with the controlling valve 18, and which pipe 17 conveys the crude petroleum under pressure to the atomizer.

The atomizer, shown in detail in Fig. 2, consists of the pipe nozzle 19, having one of 35 its ends connected to the body of the valve 18 of the oil pipe 17, and having its opposite end restricted or substantially closed, with the exception of the minute opening or aperture 20, through which the crude petroleum 40 under pressure is discharged in an exceedingly fine stream. The nozzle 19 projects into the steam casing or steam chamber 21 through the packing box 22 provided in one of its ends, and for adjusting the position 45 of the nozzle 19 within the steam casing 21, the nozzle 19 is provided with the threaded portion 23, upon which is screw threaded the adjusting nut 24 which is adapted to bear against the gland 25 of the packing 50 box 22 of the steam casing. The steam casing 21 is provided with the substantially centrally disposed annular flange 26, for securing the steam casing 21 upon the forward end of the retort or heated chamber 6 55 through the medium of the screw bolts 27, the portion of the steam casing 21 at the outer side of the heated chamber 6 being connected to any suitable source of steam supply under pressure of approximately 60 seventy-five pounds by the steam pipe 29. The end of the steam casing 21 which projects through the front end of the chamber 6, and into the front portion of the heated chamber 6, is substantially closed by the inwardly curved end wall 30, which is provided with the centrally disposed restricted aperture 31, in proximity to and registering with the aperture 20 of the oil pipe nozzle 19, the space or distance between the aperture 20 of the nozzle 19 and the aperture 31 of the end wall 30 of the steam casing 21 being regulated by the adjustment of the oil nozzle 19 through the medium of the adjusting nut 24 to meet the exigencies of the 70 case.

By the employment of the specifically constructed atomizer above described, the crude petroleum under pressure and expansion is forced through the aperture 20 of 75

the nozzle 19 in an exceedingly minute stream, which minute stream of oil is cut transversely of its path of movement, as the same issues from the aperture 20 in the nozzle 19, by the steam which flows through the steam casing 21 toward the end of the atomizer which projects into the heated chamber 6. The steam is caused to thus cut transversely across the stream of oil by being deflected by the inwardly curved end wall 30 of the steam casing 21. This action of the steam upon the minute stream of oil again expands the same and causes the particles of the oil to become so thoroughly dispersed and decomposed that the same issues from the atomizer through the aperture 31 in an exceedingly fine mist, whereby the molecular particles of the crude petroleum will further expand and instantaneously burst into vapor or gas upon coming into contact with the previously heated air within the chamber 6, thereby causing the molecules of the finely divided mist to efficiently liberate the highly combustible and volatile components of the crude petroleum, and to efficiently separate therefrom the heavier and less volatile components of the oil. This liberation and separation of the more highly combustible and volatile components of the oil from the heavier and less volatile components, continues during the passage of the resulting vapor or gas through the heated air within the elongated heated chamber 6 toward the opposite upper end portion of the chamber.

The heavier and less volatile components of the vaporized oil will descend upon the inclined bottom of the heated chamber 6, and should there be any of the more highly volatile components contained therein, which have not been previously liberated, the same will now gasify and ascend and commingle with the vapor or gas in the upper portion of the chamber 6 containing the more volatile components, the less volatile components being subsequently discharged from the heated chamber 6 through the discharge pipe 12 above described. The vapor or gas in the upper portion of the heated chamber 6 has, by this process, been converted into a homogeneous gas containing all of the highly combustible and volatile components of the crude petroleum, which gas is led off through the conducting pipe 32 to a primary condenser, which is shown in detail in Fig. 3. The primary condenser comprises a closed housing or casing 33, through the bottom of which, adjacent to one of its ends, is screw threaded the gas conducting pipe 32, the end of the conducting pipe 32 projecting above the bottom of the housing 33 for a distance as at 34 to prevent any back flow of the contents of the housing 33 into the heated chamber 6 through the conducting pipe 32. The hous-

ing 33 of the condenser is provided with the removable end wall 35, in which is disposed the water spray nozzle 36, of any suitable construction, the spray nozzle 36 being designed to suddenly spray the heated vapor or gas as the same issues from the hood 39 to insure the homogeneity of the resulting oil, and is connected to any suitable source of water supply through the medium of the water pipe 37, provided with the controlling valve 38.

Upon the inner side of the removable end 35 of the housing 33 is the deflector hood 39, positioned upon the inner side of the removable wall 35 below the spray nozzle 36 in such a manner that the hood 39 will cover and inclose the end 34 of the conducting pipe 32, with the exception that the hood 39 is provided with the open end 40 at a point remote from the nozzle 36, whereby the hood 39 prevents the water, which is discharged from the spray nozzle 36, from entering the mouth of the conducting pipe 32, but at the same time the gas from the pipe 32 and within the hood 39 passes outwardly through the opening 40 of the hood into the housing 33, to be acted upon by the water which is sprayed upon the gas from the spray nozzle 36 for primarily condensing the gas. The partially condensed gas and the water are led off from the housing 33 through the outlet 41 secured in the bottom of the housing 33 at the end opposite to that into which the gas is discharged, the partially condensed gas and water pass through the outlet pipe 41 into the pipe coils 42, in which the gas is finally condensed, and thereafter the finally condensed gas and the water are discharged from the coils 42 into the receiver 43, provided with any suitable form of gage or sight glass 44, and in which receiver the finally condensed oil will rise to the top of the receiver, and the water, of course, will settle in the bottom of the receiver, the oil being drawn from the receiver through either the pipe 45, provided with the controlling valve 46, or the pipe 47 provided with the controlling valve 48, according to the level of the oil in the receiver, the water in the bottom of the receiver being drawn off through the pipe 49 provided with the controlling valve 50.

For supplying cold water to the coil pipes 42 for condensing the gases therein, the sprinkler tube 51, provided in its under surfaces with the plurality of apertures 52, is provided. The sprinkler tube 51 is positioned above the coil pipes 42, so that the cold water will be continuously sprinkled or streamed upon the pipes 42, the tube 51 being supplied with water through the pipe 53, connected to the water supply pipe 37 and provided with the controlling valve 54. Positioned beneath the coil pipes 42 is a suitable receptacle or trough 55 for collect-

ing the water from the coil pipe 42, which water is carried off to any suitable point through the overflow pipe 56 secured in one end of the receptacle or trough 55.

8 It will be seen that by this process, that it is possible to produce a lighter and more highly volatile and combustible oil than the commercial gasoline now upon the market, and one that is free of the objectionable features and deleterious properties of the oils now in use, from the fact, that the oil produced by this process, being a homogeneous oil of low gravity, contains no heavy components which necessarily 10 become separated from the lighter and more volatile components and settle at the bottom of the automobile or other fuel tanks or reservoirs, which heavier components, being the first to be used and containing a large 15 percentage of carbon, carbonize the working parts of the motor, thereby destroying the efficiency of the more highly volatile components that are lastly used. This is not the case with the oil resulting from the 20 process constituting this invention as this oil contains none of the harmful ingredients, and being of a highly volatile nature, a less quantity of the oil is necessary to accomplish a given amount of work.

25 80 Having described my invention, what I claim as new and desire to secure by Letters-Patent is:—

25 The process of producing a highly combustible and volatile fluid from crude petroleum, consisting in storing the crude petroleum in a tank or plurality of tanks and subjecting the petroleum therein to pressure for forcing the oil through a nozzle for

discharging the oil in a minute stream into a casing co-axial with said nozzle, injecting steam into said casing for preheating and initially expanding the oil while in the nozzle and for subsequently cutting through the minute stream of oil transversely of its path for again expanding the oil for dissipating the particles of the oil, causing the same to issue from the casing in an exceedingly fine mist into one end of an expansion chamber heated to a temperature of approximately 180 degrees Fahrenheit whereby to 40 further expand the finely divided mist to cause the instantaneous and simultaneous liberation and vaporization of the highly combustible and volatile components of the entire body of the petroleum to produce a 45 homogeneous gas, allowing the gas thus produced to travel slowly through the heated expansion chamber for separating the same from the heavier and more bituminous components of the petroleum, conducting the gas to a primary condenser, suddenly spraying the gas within the primary condenser with a condensing medium to insure its homogeneity, conducting the gas thus treated to a secondary condenser, and subsequently conducting the resulting fluid to a receiver, whereby to produce a highly combustible and volatile homogeneous fluid of low specific gravity.

50 In testimony whereof I have signed my name to this specification in the presence of two subscribing witnesses.

70 WILLIAM LANDES.
